Eastman & McCartney LLP(57) **CLAIM**

The ornamental design for a tile and grout cleaning pad, as shown and described.

DESCRIPTION

FIG. 1 is a top perspective view of the tile and grout cleaning pad showing my new design;

FIG. 2 is a top plan view thereof;

FIG. 3 is a bottom plan view thereof;

FIG. 4 is a front elevational view thereof;

FIG. 5 is a back elevational view thereof;

FIG. 6 is a right side elevational view thereof; and,

FIG. 7 is a left side elevational view thereof.

The broken lines in the figures represent portions of the tile and grout cleaning pad that form no part of the claimed design.
